(57) **CLAIM**

The ornamental design for a street lamp as shown and described.

DESCRIPTION

FIG. 1 is a perspective view of the street lamp showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2;

and,

FIG. 12 is a partial enlarged view of portion 12 in FIG. 2.

The broken lines depict portions of the street lamp and form no part of the claimed design.

The dot dash lines are included for the purpose of illustrating the bounds of the enlarged views and form no part of the claimed design.
